COMBINED CIGARETTE HOLDER AND FINGER RING

Jack C. Seehase, 625 S. Phelps, Winter Park, Fla.

Filed Oct. 22, 1962, Ser. No. 72,214

Term of patent 14 years

(Cl. D85—8)

Fig. 1.

Fig. 2.

Fig. 3.

Fig. 4.

Fig. 5.

FIGURE 1 is a perspective view of a combined cigarette holder and finger ring embodying my new design;

I claim:

The ornamental design for a combined cigarette holder and finger ring, substantially as shown and described.
